SERVICE TOOL

Bernard L. La Vey, Dearborn, Mich.

Application April 6, 1944, Serial No. 529,767

3 Claims. (Cl. 294—78)

This invention relates to service tools in general and particularly to tools for facilitating removal of engines from passenger cars, trucks, boats, etc.

When servicing and making repairs on the engines of modern motor vehicles considerable time is wasted by the mechanic in getting at the engine. The design of passenger cars, trucks and busses now in use is governed by the desire for a streamlined appearance rather than accessibility and the use of deeply drawn fenders, alligator type hoods, etc. has made it necessary for the service mechanic to spend more time in disassembling the car to get at the engine and in reassembling it after the repairs have been made than is spent in actually making the repair. This has caused the cost of engine servicing to rise and ties up mechanics for long periods of time on relatively simple jobs.

In instances where anything but the most simple repairs or adjustments are to be made on the usual automobile engine, the engine must be wholly or partially removed from the chassis. This is usually done by loosening the engine fastening bolts and jacking up the engine by means of portable jacks. This is a slow and unsatisfactory operation and is a frequent cause of accidents, because the engine is at best unstably supported and any violent pulling or pushing will cause it to fall off of the jacks.

It is the principal object of my invention to provide a cheap, easily constructed and simple device for lifting the engine out of the chassis when repairs are being made. The device also supports the engine during the time it is out of the chassis and facilitates moving the engine about the shop to test benches, etc.

For purposes of illustration, I illustrate the use and application of my improved service tool in connection with a V-type engine, but it is useful with other types of engines as well.

In the accompanying drawing wherein characters of reference are used to designate corresponding parts referred to in the following description.

Fig. 1 is an elevational view of an engine supported by my improved device.

Fig. 2 is a sectional view taken as indicated by the arrows 2—2 in Fig. 1.

Fig. 3 is a perspective view of the tool itself.

Fig. 4 is a section along line 4—4 of Fig. 3, and Fig. 5 is a view along the line 5—5 of Fig. 4.

In Fig. 1, the engine 10 has had the valve cover and top-mounted accessories removed and is supported free of the chassis by my improved

service tool 11 and a chain 12. The latter may be part of an overhead monorail system or part of a simple hoist such as is found in practically every shop.

5 The service device 11 comprises a pair of angle sections 13 which are rigidly fastened together in spaced relation by bolts 14. The latter are preferably welded in place.

Securely fastened, as by welding, to the upper portions of the angle pieces midway of the length thereof is a block 15. The block is provided with a central bore which carries a threaded bolt 16. The latter is freely slidable in the bore and is provided with a handle 17 at the top thereof and a flange 18 at the bottom end.

A wing nut 19 having handles 21 is threaded on the bolt 16, a washer 20 being provided in accordance with usual practice. The flange 18 is rectangular in shape and is relatively narrow in cross section so that it is adapted to be readily received into the opening 22 in the engine block 23.

25 As will be understood from the drawings, my engine removing and supporting tool is simple to use.

When it is desired to remove an engine from a chassis, the engine valve cover is removed and the device 11 is placed on top of the engine 30 with the holding flange 18 positioned parallel to the angle pieces 13 as indicated by the dot-dash lines in Fig. 5. The wing nut 19 is then loosened, the screw 16 being held from rotating by means of the handle 17, and the flange 18 35 is inserted into the opening 22 and then rotated ninety degrees by means of handle 17. The wing nut 19 is then tightened by means of handles 21 and the tool is thus locked to the engine as clearly shown in Fig. 2.

40 A chain, such as 12 in Fig. 1, may now be hooked to one of the bolts 14 and after removing the fastening bolts the engine is ready to be removed from the chassis.

In some instances the repairs needed do not 45 require full removal of the engine. In cases when it is necessary only to tip the engine, the chain may be hooked to the forward bolt 14 as shown in the dot-dash lines of Fig. 1. The bolts 14 are preferably placed in such positions that one 50 of them will be approximately in line with the center of gravity of the engine so that the latter can be removed and shifted about the shop with the use of one chain only.

Having thus described one embodiment of my 55 invention by way of example, I wish it under-

stood that I do not intend thereby to limit the invention in the broader aspects thereof, except as defined in the claims appended below.

I claim:

1. As a new article of manufacture, a tool for lifting engines comprising, a pair of elongated bars disposed in spaced parallel relationship; a threaded block carried by said bars substantially centrally thereof; a bolt carried by said block; a holding flange carried by the lower end of said bolt; a handle upon the upper end of said bolt for positioning said flange, and means for tightening said bolt.

2. As a new article of manufacture, an engine lifting and supporting tool comprising, a member adapted to rest on the engine and overlie the valve opening thereof; adjustable means carried by said member comprising a flanged bolt

adapted to be inserted into said valve opening; means on said bolt for positioning the flange and for adjusting the same such that it tightly engages the inner marginal edge of said opening, and means on said member for engaging a hoisting rig.

3. In an engine lifting tool in combination, a pair of angle bars; means securing said bars to one another in parallel spaced relationship; a threaded block carried by said bars; threaded bolt carried by said block having means attached thereto for clamping an engine to the bottom flanges of said bars; a handle on one end of said bolt for positioning said clamping means; a wing nut carried by said bolt for tightening said clamping means and means on said bars for engaging a hoisting means.
